UNITED STATES PATENT OFFICE.

JOHN KNIERIEM, OF NEW YORK, N. Y., ASSIGNOR TO HARRY HILFMAN, OF NEW YORK, N. Y.

DESIGN FOR A CHANDELIER.

Application filed April 14, 1928. Serial No. 26,326. Term of patent 3½ years.

To all whom it may concern:

Be it known that I, JOHN KNIERIEM, a citizen of the United States, residing in New York, in the county of Queens and State of New York, have invented a new, original, and ornamental Design for a Chandelier, as shown, of which the following is a specification, reference being had to the accompanying drawing, forming part hereof, in which the figure is a perspective view showing my device.

I claim:

The ornamental design for a chandelier, as shown.

JOHN KNIERIEM.
